UNITED STATES PATENT OFFICE.

ABBOT AUGUSTUS LOW, OF BROOKLYN, NEW YORK.

CARD-CANCELING MACHINE.

SPECIFICATION forming part of Letters Patent No. 591,630, dated October 12, 1897.

Application filed May 9, 1896. Serial No. 590,811. (No model.)

To all whom it may concern:

Be it known that I, ABBOT AUGUSTUS Low, a citizen of the United States, residing in the city of Brooklyn, in the county of Kings and

5 State of New York, have invented certain new and useful Improvements in Card-Canceling Machines, of which the following is a specification sufficient to enable others skilled in the art to which the invention appertains to 10 make and use the same.

My improvements relate to the form of card-canceling machine set forth in Letters Patent No. 517,051, issued to me March 27, 1894, and in my concurrent application filed April 13, 15 1896, Serial No. 587,267, in which latter provision is made for the use of an automatic counting device which is thrown in or out of action by the adjustment of a pusher on the hand-lever by which the punch is operated.

20 The object of my present invention is the provision of means whereby the ordinary counting device operated by hand may be employed in connection with my card-canceling machine; and the invention consists 25 in a receptacle upon the standard or other stationary part of the machine adapted to receive the counting device and hold it in proper relation to the punch-lever, said receptacle being formed with a retaining-cover 30 of peculiar construction, whereby the counting device may be turned into or out of position for engagement with the punch-lever without removing said cover or the counting device, as hereinafter more fully described.

35 In the accompanying drawings, Figure 1 is an elevation of my card-canceling machine provided with holder or counting device; Fig. 2, an elevation of the holder with counting device and cover in place; Fig. 3, a similar view with cover removed; Fig. 4, a top view of holder and counting device; Fig. 5, a horizontal section of holder and cover on plane of line 5 5, Fig. 2; Fig. 6, an elevation of inner side of cover; Fig. 7, a side elevation of the counting device; Fig. 8, a front elevation of the same.

45 B is the supporting bed or frame, formed with the overhanging standard S, within the vertical portion S' of which the upper end of 50 the punch P is mounted. The punch P is of any ordinary construction or arrangement of parts, or it may be replaced with a stamping

or marking device. The punch P is pressed down against the resistance of a coiled spring by an eccentric lever L of any ordinary or 55 well-known construction.

Upon the standard S' is formed or secured the holder H, in which the counting device C is placed. This counter C is of the kind usually employed in counting by hand, consisting of a short cylindrical barrel or casing c, from the periphery of which projects the press-lever c', the depression of which operates the counting mechanism within. The counter has also externally a finger-ring R, 60 hinged to one of its sides, as well as the projecting knobs K K', by which the counting mechanism in the interior may be set back, the opposite side of the case being formed with the sight or window W, through which 65 the numerals indicating the count may be observed.

The compartment h in the holder H is preferably of cylindrical form to correspond with and receive the counter C. Its upper side is 75 formed with the slot h', through which the press-lever c' of the counter projects. This slot is elongated sufficiently to allow the counter to be turned within the holder to bring the press-lever c' either into or out of engagement with the lever L when the latter is depressed.

One side of the compartment h in the holder is closed by a detachable cover D, the other side being permanently closed by the wall h² 85 with the exception of the opening h³, through which the window W of the counter C projects or may be seen.

Parallel slots d d' extend inward from the edge of the cover D and admit of the projection of the handle-ring R, as shown in Figs. 2 and 4.

The cover D is held in position on the barrel of the holder H by a thumb-screw T on one side and a headed pin N on the other. 95 The thumb-screw T passes through a concentric slot d² and the pin N enters a like concentric slot d³ through a transverse opening d⁴.

The inner side of the cover is formed with 100 an annular collar or flange d⁵, which serves to centralize and hold the cover in place and upon which it turns during the adjustment of the position of the counter.

To insert the counter C, the thumb-screw T is withdrawn and the cover D removed. The counter C is then placed within the compartment h, with its window W projecting 5 through the opening h³ and with its handle R projecting outward at right angles. The cover is then returned to position, the slots d d' receiving the adjoining portions of the handle-ring R, the pin N entering the concentric slot d³ through the opening d⁴ and the thumb-screw T being passed through the slot d³ and into engagement with the female screw-thread h⁴.

If it be desired to bring the counter into 15 use, the thumb-screw T is first loosened and the counter C and cover D are moved, through the medium of the handle R, so as to bring the push-lever c' under the action of the lever L, this being the position shown in solid lines 20 in the drawings. The thumb-screw is then tightened, securing the cover D and counter C in this position, when, at each depression of the lever L, the pusher-lever c' will be depressed to operate the counting mechanism. 25 If it is desired to dispense with the use of the counter C temporarily, the thumb-screw T is again loosened and the cover and counter, by means of a handle R, are swung over until the push-lever is beyond the reach of the 30 hand-lever, the thumb-screw being again tightened to hold the parts in this position.

By my invention I am enabled to employ a 35 counting device in conjunction with my ticket-punch, which counting device, when not in use upon the punch, is available for use for other purposes, the application and re-

moval of the counter to the punch and its adjustment thereon being effected by simple and convenient means.

What I claim as my invention, and desire 40 to secure by Letters Patent, is—

1. The combination of a card-canceling machine, a holder for a counting device formed integral with the frame of the canceling-machine, a counting device resting loosely in 45 said rigid holder, and a cover for said holder engaging with said counting device and secured adjustably upon the holder for the purpose of regulating the position of the counting device, substantially in the manner and 50 for the purpose described.

2. The combination of the punching mechanism with the lever L, the receptacle H, the counter C, and push-lever c', the cover D, formed with the slots d, d', d², d³, and d⁴, the 55 handle R of the counter, the pin N, and the thumb-screw T, the whole arranged and operating substantially in the manner and for the purpose described.

3. The combination of the punching mech- 60 anism, the lever L, holder H, formed with the opening h³, the counter C, with its push-lever c', the cover D, formed with the annular flange d⁵, and slots d, d', d², d³, the pin N, and the thumb-screw T, the whole arranged and 65 operating substantially in the manner and for the purpose described.

ABBOT AUGUSTUS LOW.
